UNITED STATES PATENT OFFICE

PROSPER L'ORANGE, OF STUTTGART, GERMANY

SPRAY-CONTROLLING DEVICE FOR ROAD-SCAVENGERING MACHINES

Application filed July 9, 1928, Serial No. 291,282, and in Germany June 15, 1927.

This invention relates to a street scavenger-
ing machine and consists in the combination
with a spray-producer, and with means whereby
the extent of the spray can be regulated
5 transversely as well as longitudinally of the
machine, and of a universally movable hand
lever whereby said regulating means are con-
trolled for effecting a regulation of the spray
in both directions.

10 Since in this arrangement there is only one
operating lever, the regulation of the spray to
meet varying road conditions will be greatly
facilitated, particularly if the required move-
ments of the lever are in accordance with nat-
15 ural promptings, for instance if the regula-
tion of the spray is co-directional with the
movement of the lever grip.

Fig. 1 of the accompanying drawings re-
presents a sectional side view of one form of
20 the device,

Fig. 2, a front view of the same,

Fig. 3, a sectional side view of a modified
form of the device, and

Fig. 4, a front view of the latter.

25 In both constructions the spray-producer
consists of a cylinder *a* which receives water or
other liquid from a conduit *n* and which has
a series of perforations *b* through which the
liquid is discharged in a spray the extent of
30 which, transversely and longitudinally of the
machine, depends upon the arrangement of
the perforations in the cylinder wall. This
extent can be regulated by means of valve ele-
ments whereby more or less of the perfora-
35 tions may be closed.

In the arrangement of Figs. 1 and 2 there
are two valve elements one of which is com-
posed of a piston valve *c* arranged inside the
cylinder and adapted for slidable adjust-
40 ment therein. The other valve element consists of
a sleeve *g* which is adapted to be rotated about
the cylinder and which has a cut-away por-
tion *h* through which all the perforations *b*
can be exposed when required, while the num-
45 ber of open perforations can be reduced at
will by a rotary adjustment of the sleeve. A
toothed rim *i* on the head of the sleeve *g*
meshes with a toothed sector *k* which is se-
cured to a shaft *o* carried, parallel with the
50 cylinder *a*, in a bracket *m* on the conduit *n*.

A fork *p* at the outer end of the shaft *o* holds,
one a pivot pin *q*, a hand lever *r* whereby the
shaft *o* and sector *k* can be rocked for rotat-
ing the valve element *g*. The lever, which
is free to rock independently about the pivot *q*
55 in the longitudinal plane of the shaft *o*, car-
ries, near the fulcrum of the lever, a pivot pin
s which is normally in alignment with the
shaft *o*. Loosely arranged on the pivot pin
s is an arm *t* which is thus constrained to fol-
low the rocking movements of the lever *r* in
the direction A—B (Fig. 1) while it is un-
affected by the hand-lever when the latter is
rocked in the direction C—D (Fig. 2) for
60 adjusting the valve *g*. The valve element *c*
is controlled by a rod *f* which passes through
a gland *d* and which is engaged by a fork *u* at
the free end of the arm *t* so as to cause the
valve to be adjusted when the two levers rock
about the pivot *q*.

The left side of Fig. 1 is turned towards the
front end of the machine, and the lever *r* will
therefore have to be turned rearwards for re-
stricting the spray in the longitudinal direc-
75 tion, this being a natural movement. So is
also the movement indicated in Fig. 2 for re-
stricting the extent of the spray from the side
of the machine, the lever being for this pur-
pose turned from its more or less vertical po-
sition towards the centre of the machine, i. e.,
80 in the direction in which the spray is to be re-
stricted.

In the arrangement shown in Figs. 3 and
4 the regulation of the spray is effected by
means of a single valve element *c*¹ which is
adapted for rotary as well as slidable move-
ment. The valve has an edge *v* whereby, on
being rotated, it restricts the spray in a trans-
verse direction, an edge *w* whereby, on being
moved axially, it restricts the spray in the
longitudinal direction. A rod *f*¹ which con-
trols the valve, is fitted at its outer end with
a crank *x* which is engaged by a fork *u*¹ situ-
ated at one end of a double-armed hand-lever
*r*¹ which, like the lever *r* of the previous con-
struction, is mounted on a pivot pin *q* in a
fork *p* at the end of a rotatable shaft *o*.

When the hand lever is rocked in the direc-
tions C—D (Fig. 4) it turns the valve *c*¹
through the medium of the crank *x*. When it
100

is rocked in the directions A—B (Fig. 3) it acts on the crank for displacing the valve in the longitudinal direction.

I claim:

- 5 1. In a street scavenging machine, the combination with a spray-producer, and with means in said spray-producer for regulating the extent of the spray transversely as well as longitudinally of the machine, of a hand-lever capable of universal movement about a fulcrum, and connection between said lever and the spray-regulating means for controlling the latter.
- 10 2. A structure as claimed in claim 1 where-
in the arrangement is such that the regulation of the spray is codirectional with the move-
ment of the lever grip.
- 15 3. In a street-scavenging machine, a spray-producer comprising a perforated cylinder, two valve elements cooperating with said cylinder for closing the perforations, one of said valve elements being rotatable about and the other slideable relative to the cylinder, a toothed sector controlling the
20 rotatable valve element, a shaft arranged par-
allel with the cylinder and carrying said sec-
tor, a hand-lever pivoted to said shaft so as to
participate in the rotary movements of the
25 latter and allow of being rocked independ-
ently in the longitudinal plane of the shaft, a
pivot pin carried by the hand-lever near its
fulcrum and held normally in alignment with
the shaft, a forked arm mounted loosely on
30 said pivot pin, and a rod connected to the slid-
able valve element and engaged by the fork of
said arm so as to cause said latter valve to be
adjusted when the hand-lever is rocked.
